Primary Examiner — Keith J Wilson

(57) **CLAIM**

The ornamental design for an electric sprayer, as shown and described.

DESCRIPTION

FIG. 1 is a front perspective view of an electric sprayer, showing my new design;

FIG. 2 is a front view thereof;

FIG. 3 is a rear view thereof;

FIG. 4 is the enlarged planar graph on the left side;

FIG. 5 is the enlarged planar graph on the right side.

FIG. 6 is a top view thereof; and,

FIG. 7 is a bottom view thereof.

The broken lines in the drawings illustrate the portions of the electric sprayer, which form no part of the claimed design.

1 Claim, 7 Drawing Sheets
